[57] CLAIM

The ornamental design for female urinary device or the like, substantially as shown and described.

DESCRIPTION

FIG. 1 is a front perspective view of the female urinary device showing our new design;

FIG. 2 is a front elevational view thereof;

FIG. 3 is a right side elevational view thereof;

FIG. 5 is a top view thereof;

FIG. 6 is a bottom view thereof; and

FIG. 7 is an exploded front elevation of the urinary device, the spongy pad element is partially fragmented for clarity of illustration.

FIG. 2**FIG. 3****FIG. 4****FIG. 5****FIG. 6****FIG. 7****FIG. 1**
